ATTORNEY

UNITED STATES PATENT OFFICE.

WILLIAM M. WADE, OF TOPEKA, KANSAS.

DESIGN FOR AN ADVERTISING-CABINET.

58,844.

Specification for Design.

Patented Aug. 30, 1921.

Application filed December 7, 1920. Serial No. 429,000. Term of patent 14 years.

To all whom it may concern:

Be it known that I, WILLIAM M. WADE, a citizen of the United States, residing at Topeka, in the county of Shawnee and State of Kansas, have invented a new, original, and ornamental Design for an Advertising-Cabinet, of which the following is a specification, reference being had to the accompanying drawings, forming a part thereof.

The figure is a perspective view of the advertising cabinet, showing my new design.

I claim—

The ornamental design for an advertising cabinet, as shown.

WM. M. WADE.
